ELECTRICALLY CONTROLLED PLATEN OPERATING MECHANISM FOR TIME STAMPS

Frederick Q. Rast, Rochester, N. Y., assignor to
International Business Machines Corporation,
New York, N. Y., a corporation of New York

Application February 11, 1944, Serial No. 521,933

12 Claims. (Cl. 101—287)

1

This invention relates to time stamps and more particularly to the type in which the impression is effected by a power operated means, in contradistinction to the type wherein the impression is effected manually.

The invention primarily concerns the platen operating mechanism and it has for its principal object the provision of an improved mechanism that will provide the clean sharp print without reliance upon the use of a solenoid for directly actuating the platen.

While solenoids of various purposes have been found efficient in their function, their use usually required the provision of a non-repeat platen operating mechanism, which expedient is eliminated by the present invention. Furthermore, to secure sufficient power to operate the platen to provide the clean sharp print, solenoids of sufficient capacity were required, and required considerable electric power for their complete energization. Since the circuits of such solenoids were directly in the circuit which included the paper actuated contacts, difficulties in maintaining clean and efficient contacts resulted. In the present invention all of such difficulties are completely avoided since the platen operating mechanism is operated by a spring operated drive, which energy is constantly stored and maintained for use as a main power drive as the time stamp is called into operation.

A supplemental object of the invention is the provision of an electrical motor and driving connections between the electric motor and the spring drive which automatically maintain the spring drive completely wound.

A still further object is to provide an improved arrangement by means of which the unwound condition of the spring drive is detected and a rewinding operation by the electrical motor operating is automatically effected.

A still further object is to provide a novel form of means to prevent over-winding of the spring drive and possible resultant damage to the parts.

More specifically the last named object is attained by the provision of a worm wheel drive intermediate the motor and the spring drive. During the time that the spring drive is being wound the worm wheel functions in a normal manner and this normal operation is derived by balancing the power to coil the spring against a balancing spring, which latter provides a thrust bearing for a floating shaft of one element of the worm wheel drive. In the rewinding operation when the power required to wind the coil spring is greater than the balancing spring, then the worm wheel drive functions in another manner,

2

the operating characteristics being such that the floating axis shifts laterally to terminate the operation of the electric motor and the spring rewinding operation.

5 Another object of the invention is to provide an arrangement which enables the operation of the mechanically operated platen operating means without damage of parts in the event that the platen is obstructed or prevented from receiving its invariable printing movement.

A still further object of the invention is to provide an escapement mechanism which comprises a mechanical control for the platen operation.

15 A still further object is to provide an electromagnetic control of the aforementioned escapement mechanism and operatively coordinated in such a manner that a small electromagnet or solenoid can be used for initiating platen operations.

20 A still further object ensuing directly from the provision of a small electromagnet is to provide a circuit closing contact device operable by the paper inserted in the machine. Since, in the present machine, the electromagnet does not require large currents for its energization, contact troubles are greatly minimized if not completely eliminated.

25 Other objects of the invention will be pointed out in the following description and claims and illustrated in the accompanying drawings, which disclose, by way of example, the principle of the invention and the best mode, which has been contemplated, of applying that principle.

30 In said drawings:

35 Fig. 1 is a view in side elevation of the right side of the machine, relative to the operator, the lower casing being shown broken away to show the interior parts constituting the present improvement.

40 Fig. 2 is a longitudinal sectional view taken on the line 2—2 of Fig. 1 and shows in plan the parts constituting the present invention.

45 Fig. 3 is a transverse sectional view taken on the line 3—3 of Fig. 1 which is substantially the mid-portion of the machine.

50 Fig. 4 is a transverse sectional view taken on the line 4—4 of Fig. 1 and shows the construction of the spring operated power drive of the present invention.

55 Fig. 5 is a view in side elevation taken on the line 5—5 of Fig. 1, showing particularly the escapement operated means for effecting the reciprocation of the platen by the spring power drive.

Fig. 6 is a view taken on the line 6—6 which is substantially at the front portion of the machine and shows particularly the platen and the related operating mechanism.

Fig. 7 is a detached view showing the construction of the escapement mechanism as well as the electromagnetic control therefor.

Figs. 8 and 9 are views of certain of the parts shown in Fig. 7 but in moved position.

Fig. 10 is an electrical wiring diagram of the electrical instrumentalities involved in the present invention.

Fig. 11 is a detached view showing the parts associated with the platen operating mechanism.

Fig. 12 is a plan view of the paper actuated contact operating mechanism.

The entire time stamp is mounted upon a base casting 10 which provides the entire supporting means for the novel platen operating mechanism. The latter mechanism is enclosed by a casing 11 (Fig. 11). By means of a pivot pin 12 carried by the bottom casing the printing head 13 is pivotally mounted. The printing head 13 constitutes the type wheels, the clock controlled drive, time indicating mechanism, ribbon feeding mechanism, etc., all of which are fully shown and described in detail in the patent to L.C. Bishop et al., No. 1,798,583, dated March 31, 1931. The mechanism in the printing head is not shown herein since the present invention relates to novel means for operating and controlling the impression taking means, or platen. For an understanding of the present invention, it is sufficient to understand that the time printing means consists of a group of wheels 14 (Figs. 1 and 11) which are preferably time and date printing wheels to print such information upon the papers to be stamped. The printing head 13 has a separate enclosing casing 15 (Fig. 1) and it will be observed that the front portions of the casings 15 and 11 are so disposed as to provide a deep unobstructed opening 16 for receiving the papers to be stamped. Of course, the printing head 15 is suitably latched to the base portion of the machine so that the time and date printing wheels 14 are immovable to receive the percussive blow from the platen.

The platen 17 is rectangular in shape as will be noted from Figs. 1 and 11 and carries at its top an impression taking material 18, preferably of rubber. Depending from the platen 17 is a cylindrical stem 19 fitting in a cylinder 20 fixed in any suitable manner to the base casting 10. To provide an additional guide for the movement of the platen 17 the casing 11 is provided with a flanged aperture 21 of the same outline as the platen 17, that is, rectangular, and suitably guides the platen in its reciprocating movement. The platen 17 is, as shown in Fig. 1, normally below the upper horizontal surface of the casing 11 to provide an unobstructed positioning of the papers to be stamped.

The preferred form of means which provides the operative connection between the platen operating mechanism and the platen is best shown in Figs. 5, 6 and 11. Referring to Figs. 5 and 6, it will be seen that upstanding from the base 10 are brackets 22 and 23 in which is journaled a shaft 24 and secured to the shaft is an arm 25 and, as shown in Fig. 11, arm 25 projects within a slot 20a of the cylinder 20 and underlies the bottom of the stem 19 of the platen 17. To the rock shaft 24 there is secured an arm 26 and

loosely mounted on the rock shaft 24 is a plate 27 and interposed between the arm 26 and the plate 27 is a normally tensioned spring 28. Spring 28 draws arm 26 against plate 27 until edge 27a strikes spring stud 26a carried by the arm 26. Obviously, when the plate 27 is rocked counterclockwise, the arm 26 will be rocked through the interposed spring 28 in the same direction and accordingly the shaft 24 will be rocked in a similar direction to cause the arm 25 to elevate the platen 17 to effect the percussive printing action. In the position of the parts shown in Fig. 5 cam portion 29 of the plate 27 rests on the top of one of the series of operating studs 30. Such studs are equiangularly disposed on an escapement disk 31 and are coextensive with the step of movement given to the escapement disk 31 for each operation of the machine. Therefore, in the angular movement of the escapement disk 31, controlled in the manner to be subsequently explained, the stud 30 in cooperation with the cam portion 29 will, in such step of movement, positively rock the plate 27 counterclockwise, and through spring 28 rocking arm 26, shaft 24, and arm 25 in the same counterclockwise direction. This will positively force the impression block 17 to impress the paper to be stamped against the printing wheels.

In the actual operation of the machine the step of movement given to the escapement disk 31 by a spring operated drive is very rapid and accordingly the platen 17 is operated with a hammer blow, to thereby provide the desired clean impression. It may be possible that the platen will be stopped by the type wheels before the plate 27 is given the extent of movement provided by the step of movement of the escapement disk 31. However, no damage will be caused because it is obvious that further movement of the plate 27 after the platen has been obstructed will merely tension the spring 28 until the operating stud 30 finally clears the cam portion 29 of the plate 27.

The position of the parts 30, as the operating stud 30 is about to clear the plate 27, is shown in Fig. 11, it being obvious that a slight additional clockwise movement of the escapement disk 31 will cause the stud to clear the cam portion 29, whereupon the platen is now free to drop to normal position by its own weight, and parts connected thereto. If so desired, any suitable tensioning means may be attached to the platen or any parts which are given a similar movement to positively restore the platen to its normal position. However, by proper dimensioning of the parts and selection of suitable materials, gravity alone may be depended upon for restoration of the platen to normal.

Means to effect an equiangular step of movement of the escapement disk 31 for each operation of the machine, that is, for each stamping or printing of the inserted paper, will now be described, particularly in connection with Figs. 5, 7, 8, 9, 10 and 11.

The escapement disk 31 is provided with escapement teeth 32 which are disposed around the periphery to correspond with the angular positioning of the operating studs 30. Associated with the teeth 32 is an escapement mechanism which consists of a positively operated escapement pawl 33 and a spring operated stop pawl 34 and to provide the movement of such pawls there is provided a solenoid 35. It will be ob-

served from Figs. 2 and 5 that this escapement control is mounted on the base 10 of the machine.

The solenoid 35 has a core 36 having a reduced portion 37 receiving a lug 38 of a link 39. An elongated slot 40 of the link 39 receives a stud 41 secured to the base of the machine, thereby guiding the link 39 in its movement effected by the solenoid 35 to the right and its retraction by a spring 42 connected to the aforementioned link 39. The link 39 is connected to the positively operated escapement pawl 33 by a pin 43. A stud 44 passing in the base 10 provides the pivotal mounting for the stop pawl 34 and the escapement pawl 33. It will be noted that while the stop pawl 34 is superimposed with respect to the escapement pawl 33 the latter has a bent-up portion 45 (see also Fig. 5) which brings the terminations of the pawls 33 and 34 in the same plane and therefore in a position to intercept one of the teeth 32 of the escapement disk 31. A spring 46 is interposed between the stop pawl 34 and the positively operated escapement pawl 33 and normally, that is to say, after a previous operation of the platen, one of the teeth 32 of the escapement disk 31 normally abuts a shoulder 47 of the escapement pawl 45. (See Fig. 7.)

Referring to Fig. 10, reference numeral 48 represents electrical contacts which may be manually closed, or by the paper to be stamped or printed when it is inserted in the machine. From the simple electrical circuit in Fig. 10 it is clear that closure of such contacts will energize the solenoid 35 and the latter will attract its core 36 to move the link 39 to the right as shown in Fig. 7 to rock the escapement pawl 33 clockwise, withdrawing the shoulder 47 from the tooth 32 with which it is engaged.

Assuming now that the spring drive has been wound up sufficiently to drive the escapement disk 31, the latter is now free to rotate to operate the platen in the manner previously described.

Fig. 8 shows the position of the parts wherein the escapement pawl 33 has been rocked sufficiently to release the escapement disk 31 and in such position the spring 46 is tensioned so that a shoulder 48 of the stop pawl 33 bears against the side of the tooth 32. The escapement tooth 32 will, of course, pass by the shoulder 48 as the escapement disk 31 is moved a single step. When the link 39 is at its extreme position at the right, the increased tension of the spring 46 will rock stop pawl 34 sufficiently so that shoulder 48 is now in the path of the following tooth 32. (See Fig. 9.) Ultimately the tooth 32 will abut the shoulder 48 to stop the disk 31. When the solenoid 35 is deenergized, spring 42 will now shift link 39 to the left. Since the shoulder 47 abuts the shoulder 48, this will rock the stop pawl 34 slightly in a counterclockwise direction, withdrawing the shoulder 48 from an abutment relationship with the following tooth 32, whereupon the disk 31 will move very slightly until the following stop tooth 32 engages the shoulder 47 of the escapement pawl 33. The parts are now in the position shown in Fig. 7, ready for a subsequent operation.

The spring operated means for providing the step-by-step movement of the escapement disk is preferably provided by the usual form of spring barrel, well known in clock mechanisms, typewriters, etc. A somewhat similar means is preferably utilized herein and comprises a coil spring 50 (Fig. 4) which, as it is permitted to uncoil,

provides the power to rotate the escapement disk 31. One end of the coil spring is secured to a winding shaft 51 by a pin 52, the other end of the coil spring 50 enveloping one of the series of studs 53. The coil spring 50 is mounted in a cage which comprises the escapement disk 31 and a parallel circular disk 54. The disks 31 and 54 are spaced apart by spacing tubes 55 (Figs. 1 and 4) through which pass fastening screws 56. At each end of the screws 56 the aforementioned operating studs 30 are screwed. By this arrangement a rigid spring carrying cage is provided.

The winding shaft 51 may be rotated in a clockwise direction (Fig. 4) by any suitable supplemental power operated means to store up the necessary spring power but preferably this is provided by an electric motor 57 which is carried by a sub-base frame 58 fastened by any suitable means to the base plate 10. This motor may be of any suitable design adapted to perform efficiently by the current supply with which it is connected and have sufficient torque to rotate shaft 51 to wind up the coil spring 50. The gear driving connection intermediate the motor 57 and the spring cage will now be described.

The armature shaft of the motor 57 has secured thereto a worm wheel 59 (Fig. 3) meshing with a worm gear 60 carried by a shaft 61. The latter is rotatably supported by a pair of brackets 62 extending upwardly from the base plate 10. A supplemental support plate 63 is also provided to give additional support. Between the brackets 62 the shaft 61 is provided with worm wheel threads 64 in mesh with a worm gear 65 secured to a worm wheel support shaft 66 which extends at right angles to the shaft 61. The shaft 66 is a short shaft and is supported by a pair of brackets 67, one of which is shown in Fig. 2, both being supported by the base plate 10. Shaft 66 has secured thereto a pinion 68 meshing with a gear 69 which is fastened to the spring winding shaft 51. The above described gearing aside of having a special function to be subsequently described provides a reduction gearing between the motor 57 and the spring winding shaft 51. The gearing is so arranged that with the proper direction of rotation of the motor the shaft 51 will be turned clockwise. Since normally the escapement disk 31 is held by the aforementioned escapement mechanism, it will be evident that in rotating the spring drive shaft 51 clockwise the coil spring 50 will be wound but movement to the spring cage including the escapement disk 31 will be effectively prevented by the cooperation of the escapement pawl 45 with a tooth 32 of the escapement disk 31. Through the gearing aforementioned, the coil spring 50 is wound until it has been wound sufficiently, whereupon a certain operation will be effected to prevent over-winding of the spring and possible damage to any parts of the machine. The automatically operated mechanism for effecting this function will now be described in detail. This arrangement is best shown in Fig. 3.

Integral with the shaft 61 is a disk or flange 70 and interposed between the flange 70 and a washer 71 which is loose on the shaft 60 is a coil spring 72 encircling the extremity of the shaft 61. The spring 72 is normally under compression so that the spring will urge worm gear 60 against plate 63 and the washer 71 against the balls of a ball bearing race 74 which is carried by the support plate 63. The expansive strength of spring 72 is so selected as to prevent any transverse movement of the shaft 61 to the left

while the coil spring is being wound up from a completely uncoiled condition and the worm drive 64-65 then functions as a normal drive until a predetermined wound condition is reached. As the shaft 61 (Fig. 4) is continually rotating in a clockwise direction to wind the coil spring 50 from a completely unwound condition, the power required by the motor will be increased until at a nearly-wound condition of the spring coil 50, or even when its maximum wound condition obtains, further winding operations will be effectively prevented by the following operation.

When this predetermined load on shaft 61 is reached the worm wheel 64 is still attempting to rotate the worm gear 65 now held relatively stationary, or nearly so, but is unable to do so when the power to drive shaft 66 exceeds the force of the balancing spring 72. At this time, worm wheel threads 64 acting on worm gear 65 will now cause shaft 61 to be fed to the left as it is being rotated, since shaft 61 is free to so move due to the absence of a thrust bearing at the left. This lateral movement of shaft 61 continues until a point is reached where the flange 70 of shaft 61, in cooperation with a stud 75 of a lever 16, rocks said lever so as to open an electric switch to disconnect the current supply from the motor. The electrical means for initiating the operation of the motor 57 when a completely unwound condition of the spring drive is discerned will now be explained.

Pivotedly mounted on one of the studs 53 (Fig. 4) is a feeler lever 80 urged by a spring 81 so that it is pressed at all times against the outermost convolution of the spring 50. When the spring is completely unwound as shown in Fig. 4 a head portion 82 of the feeler lever 80 will, during a certain stepping movement of the spring cage, make contact with and operate a lever 83 secured to a transverse shaft 84 suitably journalled in a recess of the base plate 10. The rock shaft 84 carries at its extremity a switch operating arm 85. The rocking of the shaft 84 is effected upon a completely unwound condition of the spring 50 and the rocking of the lever 85 to the right (Fig. 6) will push inwardly the "on" switch button 86 of any suitable form of switch. The switch S is preferably of a type known as the "Mu" switch constructed as shown in the Patent No. 1,780,758, dated November 4, 1930. The elementary parts of this switch are diagrammatically shown in Fig. 10 wherein it will be noted that the contact carrying switch blade 87 is anchored at 88, the characteristics of the preferred form of switch being such that when the button 86 is depressed slightly by the operating arm 85 the spring blade 87 will snap to a contact making position to close contacts 89, the latter being in series with the electrical motor 57 to thereby initiate the operation of the motor resulting in the winding of the coil spring 50.

When a completely wound condition of the spring 50 is effected, or to the point desirable, it will be recalled that the flange 70 of shaft 61 is moved laterally to the left shown in Fig. 3, and by contact with the button 75 will rock the bell crank lever 76. This lever is pivoted at 90 (Fig. 2) and the front portion 91 of the bell crank lever 76 is positioned adjacent the "off" button 92 of the switch S. This will then result in the opposite snapping of the switch blade 87 to open contacts 89 to cut the current supply from the motor 57.

Hence, the motor 57 will be cut in and out of the circuit automatically the number of times this

is effected, depending, of course, on the number of times that the stamp is used for printing operations. Such operations are effected automatically without any attention on the part of the operator.

Any suitable means either manual, or paper controlled, may be provided to close the contacts 48 to initiate the imprinting operation. However, the preferred form of means will now be described.

The contact operating mechanism is constructed as a unit and is carried by a bracket 95. Pivotedly mounted on the bracket 95 by a pin 98 is a bell crank lever 96-97 which is provided with an integral upstanding paper actuated finger 99. The latter is disposed in the opening 16 to be actuated by the paper inserted in the machine to be stamped. The portion 97 of the bell crank lever has pivoted at 100 a lever 101 provided with a shoulder 102, normally engaging the extremity of a contact operating arm 103. A spring 104 interposed between the lever 101 and the bracket 95 maintains the normal position shown in Fig. 12. Obviously, when the paper strikes the finger 99 its continued movement to the rear will rock the bell crank lever 96-97 and through the lever 101 arm 103 will be rocked to close the contacts 48.

It will be recalled that closure of such contacts 30 will energize the solenoid 35 to initiate the operation of the spring driven escapement mechanism to effect the printing operation.

From Fig. 11 it will be seen that a downwardly extending lug 105 integral with the lever 101 is 35 in the path of the teeth 32 of the escapement disk 31. The release of the escapement disk 31 for a step will cause one of the teeth 32 to engage the lug 105 to rock the lever 101, thereby unlatching the arm 103. The resiliency of the operated contact operating blade is sufficient so that contacts 40 48 will thereby open, irrespective of the fact that the paper which has been printed will be maintained in contact with the finger 99 to keep the bell crank lever 96-97 in rocked position. Hence, 45 automatically operated mechanism operates to open the contacts 48 to deenergize the solenoid 35 to enable the proper performance of the escapement mechanism previously described.

While there have been shown and described and 50 pointed out the fundamental novel features of the invention as applied to a single modification, it will be understood that various omissions and substitutions and changes in the form and details of the device illustrated and in its operation 55 may be made by those skilled in the art without departing from the spirit of the invention. It is the intention, therefore, to be limited only as indicated by the scope of the following claims.

What is claimed is:

60 1. In a platen operating mechanism for a time stamp, the combination of a spring operated motor, an escapement member driven by said spring motor, a platen actuating member, an electromagnetically controlled escapement mechanism 65 for causing said escapement member to operate said platen actuating member to operate said platen to effect a paper stamping operation, and a circuit for the electromagnet controlling said escapement mechanism and including contacts 70 actuated by the paper inserted in the machine for a stamping operation to energize the electromagnet.

65 2. In a time stamp, a spring operated motor having the customary operating spring mounted upon a spring winding arbor, an escapement disk

carried by said arbor and operatively connected to said operating spring, a mechanical escapement mechanism cooperating with successive teeth of said escapement disk to release said disk for a predetermined extent of rotation, means operated by said disk for actuating a platen of the time stamp, a solenoid for controlling the escapement mechanism upon its energization, a circuit for said solenoid including contacts actuated to closed position to energize the solenoid by the paper to be inserted in the machine to be stamped, and means operable by a part of the escapement disk for enabling said contacts to take an open position irrespective of the maintained insertion of the paper within the machine after a stamping operation.

3. In a platen operating mechanism for a time stamp, the combination of a spring operated motor, an escapement member driven by said spring motor, a platen actuating member, an electromagnetically controlled escapement mechanism for causing said escapement member to operate said platen actuating member to operate said platen to effect a paper stamping operation, a circuit for the electromagnet controlling said escapement mechanism and including contacts closed by the paper inserted in the machine for a stamping operation to energize the electromagnet, and means actuated by said escapement member to cause said contacts to assume an opened position to deenergize said electromagnet.

4. In a time stamp, a spring operated motor having the usual operating spring mounted upon a spring winding arbor, an escapement disk carried by said arbor and operatively connected to said operating spring and having operating projections thereon, a mechanical escapement mechanism comprising a stop pawl and an escapement pawl cooperating with successive teeth of said escapement disk to release said disk for a predetermined extent of rotation, an arm operable by said operating projections when said disk escapes, an arm for actuating a platen of the time stamp, interconnecting means between said arms for causing said first named arm to actuate said platen actuating arm when said disk escapes, a solenoid for operating the escapement pawl upon its energization, a circuit for said solenoid including contacts actuated to closed position to energize the solenoid by the paper to be inserted in the machine to be stamped, and means operable by the escapement disk for enabling said contacts to take an open position irrespective of the maintained insertion of the paper within the machine.

5. A platen operating mechanism for a time stamp comprising a spring motor, an escapement member driven by said motor, an escapement mechanism comprising an escapement pawl and a stop pawl, the first named pawl for releasing said escapement member to be driven by said motor to an extent predetermined by said stop pawl, an actuating member for said platen, operating means operable by said escapement member, and flexible means interconnecting said operating means and said actuating member to enable an invariable operation of said escapement member to the predetermined extent irrespective of the possible obstruction of the platen.

6. A platen operating mechanism for a time stamp comprising a spring motor, an escapement member driven by said motor, an escapement mechanism for releasing said escapement member to be driven by said motor to a predetermined extent, an actuating member for said

platen, platen operating means operable by said escapement member, and flexible means interconnecting said operating means and said actuating member to enable an invariable operation of said platen operating means by said escapement member irrespective of the possible obstruction of the platen.

7. A platen operating mechanism for a time stamp comprising a spring motor, an escapement member driven by said motor, an escapement mechanism comprising a stop pawl, and an escapement pawl for releasing said escapement member to be driven by said motor to an extent predetermined by said stop pawl, an actuating member for said platen, and operating means intermediate said escapement member and said actuating member and operable by said escapement member each time the latter is released for effecting the operation of said platen to printing position.

8. A platen operating mechanism for a time stamp comprising a spring motor, an escapement member driven by said motor, an escapement mechanism comprising a stop pawl, and an escapement pawl movable to a position for releasing said escapement member to be driven by said motor to an extent predetermined by said stop pawl, an actuating member for said platen, operating means intermediate said escapement member and said actuating member and operable by said escapement member each time the latter is released for effecting the operation of said platen to printing position, a solenoid for operating said escapement pawl to releasing position, and a circuit for said solenoid including paper actuated contacts for energizing said solenoid when the paper to be stamped is inserted in the machine to a stamping position.

9. In a time stamp, a spring operated motor having the customary operating spring mounted upon a spring winding arbor, an escapement disk carried by said arbor and operatively connected to said operating spring and having operating projections thereon, a mechanical escapement mechanism comprising a stop pawl and an escapement pawl cooperating with successive teeth of said escapement disk to release said disk for a predetermined extent of rotation determined by said stop pawl, an arm operable by said operating projections when said disk escapes, an arm for actuating a platen of the time stamp, interconnecting means between said arms for causing the said first named arm to actuate said platen actuating arm when said disk escapes, a solenoid for operating the escapement pawl upon its energization, a circuit for said solenoid including contacts actuated to closed position to energize the solenoid by the paper to be inserted in the machine to be stamped, and means responsive to the operation of the escapement mechanism for enabling said contacts to take an open position irrespective of the maintained insertion of the paper within the machine.

10. In a time stamp having a platen operable to effect printing on an inserted sheet, the combination of a spring motor comprising a power spring and devices driven by said power spring, and said devices including an escapement member; escapement mechanism comprising a stop pawl and an escapement pawl coacting with said member and operable when activated to release said escapement member so that said devices, including said escapement member, are driven by said spring to an extent predetermined by said stop pawl; an actuating member for said platen;

11

and power transmitting means connecting said driven devices and said actuating member and effective to operate said platen each time said devices are driven by said spring due to the activation of said escapement mechanism.

11. Apparatus according to claim 10 and including, in addition thereto, means for activating said escapement mechanism upon the insertion of a sheet, and means responsive to the driving of said devices by said power spring to restore said escapement mechanism to its normal de-activated condition.

12. In a time stamp having a platen operable to effect printing on an inserted sheet, the combination of a driving motor operable in step-by-step fashion and including a power spring for operating said motor; escapement means co-acting with said motor and operable when activated to provide step-by-step operation of said motor, one motor operating step being effected
